United States Patent Office

Des. 218,004
Patented July 14, 1970

218,004

SLIPPER OR SIMILAR ARTICLE

Martin Sherman, Far Rockaway, N.Y.
(35 Claver Place, Brooklyn, N.Y. 11238)

Original design application Mar. 20, 1967, Ser. No. 6,302, now Patent No. 211,556, dated July 2, 1968. Divided and this application June 20, 1968, Ser. No. 17,145

Term of patent 7 years

Int. Cl. D2—04
U.S. Cl. D2—279

FIG. 1 is a front and side perspective view of a slipper or similar article, embodying my new design.

FIG. 2 is a top plan view thereof.

FIG. 3 is a side elevational view thereof.

FIG. 4 is a front elevational view thereof, and

FIG. 5 is a rear elevational view thereof.

This is a division of copending application Ser. No. D. 6,302 patented July 2, 1968, now Pat. No. D. 211,556.

I claim:

The ornamental design for a slipper or similar article, substantially as shown and described.
